UNITED STATES PATENT OFFICE.

GABRIEL ABRAHAM, OF NEW YORK, N. Y.

FLEXIBLE BELT BUCKLE.

Application filed November 12, 1924. Serial No. 749,371.

This invention relates to buckles used on belts that are intended for supporting the clothing of the wearer, and relates particularly to buckles that comprise a resilient feature to render the belt elastic for increasing the comfort of the wearer.

Among the objects of this invention is to provide a buckle having a resilient member and movable means co-operating therewith to permit the buckle to elongate under tension and thereby to increase the comfort of the wearer of said belt.

Another object of this invention is to provide a buckle having a casing and a head secured thereto in a novel manner so as to facilitate the ease of operation of said buckle by the wearer of said belt.

Another object of this invention is to provide a buckle having a resilient member and a casing for housing the same, said casing being constructed in a novel manner to co-operate in the most efficient manner with said resilient member and with the head of the buckle.

Still another object of this invention is to provide a buckle having a casing with a movable part, and a resilient member co-operating with said casing and said part to permit of movement of said part when under tension, said resilient member being so constructed as to have a high maximum deflection, any tendency of the same to tilt or stick being wholly eliminated.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof, reference is had to the accompanying drawings in which like reference characters designate the same parts in the several views, and in which—

Figure 1 is a longitudinal section of the buckle showing the same in use.

Fig. 2 is a front view of the buckle.

Fig. 3 is a sectional view taken on the line 3—3 of Fig. 1.

Fig. 4 is a sectional view taken on the line 4—4 of Fig. 2.

Fig. 5 is a sectional view on the line 5—5 of Fig. 2.

Referring now more particularly to the drawings, I show the buckle as comprising a body or casing having a plurality of rela-

tively movable and co-operating parts such as 10 and 11. Said parts or members are held securely to each other and in such manner as to permit one of them to be slideable 60 relatively to the other. For this purpose one of said parts such as the member 11 is provided with suitable extensions such as the lugs 12 to embrace the member 10 and to provide guides therefor. Both members 10 and 11 can be constructed in channel form, the member 10 having side flanges 13, while the member 11 has similar flanges 14 lying without the flanges 13. This construction provides for easy sliding movement of 70 the members, and particularly for the efficient housing of a resilient member 15. The parts 10 and 11 are provided with end flanges 16 and 17 respectively which act as abutments for the spring 15, so that as said 75 spring tends to elongate itself it will exert a pressure upon said flanges 16 and 17 outwardly in the direction of the arrows *a* so as to bring the parts of the casing into normal relation to each other as shown in Fig. 80 1. When, however, tension is exerted upon the casing to draw the parts 10 and 11 away from each other in the manner to be described hereinafter, the spring is compressed and the casing parts move outwardly of each 85 other as shown in Fig. 3.

The strap is secured in any suitable manner to the respective casing parts, but preferably I provide a frame 18 which is mounted upon the buckle in a novel manner 90 to facilitate the ease of operating the same. More particularly, said frame is secured tiltably to the casing member 11 at the free end of the buckle thus providing ample room for insertion of the strap through the frame 95 and above the casing. Said frame is provided with the usual tongue 19 for the strap 20 and slots to receive the same. The opposite end of the strap is secured in a suitable manner to the casing member 10 as at the 100 extension 21 thereof.

To prevent undue or excessive tilting of the frame preliminary to applying the belt to the person and to retain the frame in neat and adjusted relation to the buckle, I provide 105 stop means to limit the swing of the frame in the direction of the arrow *b*. Thus proper co-operation is provided between the bearings 22 which are formed on the casing member 11 and the portions of the buckle adjacent to the edges 23 of the buckle whereby the same abut against the edge 24 of the 110

casing member 11 for the purpose aforesaid. The construction disclosed herein comprises the spindles 25 which are offset inwardly relatively to the cross bars 26, thus providing the projecting lips at the edges 23.

To limit the movement of the parts of the casing, stop means are provided such as the shoulders 27 on the extension 21 which abut against the side edges 28 of the member 11 when in normal position as shown in Fig. 2, thus limiting the inward movement of the casing parts under the pressure of the spring 15. The spring itself, however, can act as a stop to limit outward movement of said parts, as when the spring is totally compressed.

The spring 15 is of the flat type and is constructed in a manner to secure a very high maximum deflection so as to provide for considerable elongation of the buckle for the sake of affording a high degree of comfort to the wearer. Moreover, the spring being of flat form may be housed within a thin casing, and since it is of rectangular form it can be rapidly assembled within the housing without the necessity of providing means to prevent a tilting thereof against the casing. With these features of advantage and superiority in view, the spring will be seen as comprising a member having a series of spaced or oppositely related curves or loops 29. More specifically, the spring comprises a series of loops lying in turn upon opposite sides of the casing, and joined by the inclined portions 30, the deflection of the spring being thus even and balanced throughout to facilitate uniformity of operation. The stability of the spring which has been indicated above is greatly facilitated in that the end arms or portions 31 which contact directly with the end flanges 16 and 17 of the casing become parallel to said flanges when the spring is slightly compressed so that the reaction of the flanges upon said arms occurs when so compressed upon the entire length of said arms thus increasing the stability of the spring against such tilting as generally occurs when a spring is deflected by a force acting upon a free end or point of the spring. The action of the arms 31 in becoming parallel to the end flanges as stated is facilitated

by the construction of the main body of the spring, which being of considerable length provides for a degree of accommodation, and also because said arms having free ends they are not subject to a counter stress such as is exerted by the loops 29 upon the connecting portions 30.

I claim:

1. A buckle comprising a body, a tiltable frame, means for attaching a strap to the body, said body having a pair of bearings remote from the strap attachment, said frame having a two-part cross-bar, the parts being spaced from each other, portions whereof form alined stems to be received within said bearings for attaching the body and frame together, and a tongue pivoted to the frame remote from the cross-bar and adapted to enter the space between the parts thereof, and portions of said cross-bar structure adjacent to said bearings being projected perpendicular to the axis of the bearings to abut against said body when the frame is tilted through a predetermined angle away from said body.

2. A buckle comprising a body, a tiltable frame, means for attaching a strap to the body, said body having a pair of bearings, said frame having a cross-bar consisting of two spaced alined portions, said portions having stems journaled in said bearings to connect the frame to the body, and a tongue mounted on the frame and adapted to enter the space between the portions of the cross-bar.

3. A buckle comprising a body having a pair of relatively movable portions, a spring to keep said body in contracted position, means for attaching a strap to one portion of the body, a tiltable frame mounted on the other portion of said body, the latter portion of the body having a pair of bearings, said frame having a cross-bar consisting of two spaced alined portions, said alined portions having stems journaled in said bearings to connect the frame to the body, and a tongue mounted on the frame remote from said bearings and adapted to enter the space between the alined portions of the cross-bar.

In testimony whereof I affix my signature.

GABRIEL ABRAHAM.
